UNITED STATES PATENT OFFICE.

SAMUEL A. GOLDBERG, OF NEW YORK, N. Y.

CUTTING-OFF ATTACHMENT FOR MACHINES FOR MAKING CORRUGATED CARDBOARD.

1,089,834.

Specification of Letters Patent. Patented Mar. 10, 1914.

Application filed September 4, 1912. Serial No. 718,561.

To all whom it may concern:

Be it known that I, SAMUEL A. GOLDBERG, a citizen of the United States of America, residing in New York, in the borough of Brooklyn, county of Kings, and State of New York, have invented certain new and useful Improvements in Cutting-Off Attachments for Machines for Making Corrugated Cardboard, of which the following is a specification.

The object of this invention is to furnish to manufacturers of corrugated cardboard an attachment for cardboard-making machines by which blanks of corrugated board of the required length are automatically cut off in a quick and reliable manner and for this purpose the invention consists of a cutting-off attachment for corrugated cardboard making machines which comprises a set of feed and guide rollers for the cardboard, laterally movable guide-plates for the board, means for actuating said guide-plates at the proper time, an adjustable stop-gage, a vertically - reciprocating knife for cutting off the proper length of blanks and a lever mechanism interposed by the stop-gage and the feed-rollers for automatically interrupting the feed-motion of the cardboard to the cutting-knife and returning the guide-plates and the stop-gage into normal position.

The invention consists further of certain details of construction which will be fully described hereinafter and finally pointed out in the claims.

In the accompanying drawings, Figure 1 represents a side-elevation of my improved cutting-off attachment for machines for making corrugated cardboards, Fig. 2 is a plan-view of Fig. 1, Fig. 3 is an elevation of the attachment, taken at the right-hand end, and Fig. 4 is also an end-elevation, showing the guide-plates moved laterally out of the way for dropping the cut-off corrugated cardboard-blanks.

Similar letters of reference indicate corresponding parts throughout the different figures of the drawings.

Referring to the drawings, a, a^1 represent a pair of feed-rollers by which the corrugated cardboard c is fed from the cardboard machine to the cutting-off attachment proper. The cardboard c is then taken up by two pairs of guide-rollers b, b^1 which are arranged in bearings of the supporting frame f of the attachment. The supporting

frame f is provided at its ends with upright standards f^1 which are extended above the horizontal portion of the frame, as shown in Fig. 1, and provided with vertical guide-slots k^2 for the oblong supporting frame k^1 of the cutting-knife k . The frame k^1 of the cutting-knife k extends transversely between the uprights f^1 of the frame f and receives intermittent vertically-reciprocating motion by means of connecting rods k^4 which are pivoted to ears k^5 at the lower part of the frame k^1 as shown in Fig. 3, said connecting-rods being strapped at their lower ends to eccentric cams k^6 on a transverse shaft s , which is supported in bearings of the side-standards f^1 , the cams being located between collars k^7 on the shaft s . Rotary motion is imparted to the actuating-shaft s by a sprocket wheel and chain transmission g, g^1, g^2 from the driving shaft S which is rotated by a belt and pulley $p^1 p$, as shown in Fig. 1. To the driving-shaft S are applied gear-wheels g^3 which transmit rotary motion to pinions g^4 on the shaft of the upper feed-roller a of the attachment and thereby to the feed-rollers a, a^1 while a chain and sprocket wheel transmission g^5, g^6, g^7 between the shaft of the upper feed-roller a transmits motion to one of the upper feed-rollers b .

In line with the horizontal portions of the supporting-frame f and symmetrically with the longitudinal axis of the cardboard making machine is arranged a stop-gage d , which is adjustably applied to a center-rod d^1 that is pivoted at its outermost end to a suspension rod d^2 which is pivoted at its upper end to ears d^3 attached to the ceiling or other support. The opposite or inner end of the center rod d^1 is pivoted to a short crank-arm d^4 at the center of a transverse rock-shaft d^5 which is supported in bracket bearings d^6 on the uprights f^1 of the supporting-frame f . One end of the transverse rock-shaft d^5 is provided with a short cam d^7 which engages one end of a lever d^8 which is fulcrumed to a plate k^1 on the upright standard f^1 and which is connected at its opposite end by a pivot-link d^9 with an elbow-lever d^{10} that is fulcrumed to the supporting-frame f and connected at its lower end with a spring-cushioned rod d^{11} that is guided in lugs d^{12} on the supporting-frame, said rod being provided with a stop-nut d^{13} at its outer end and with a helical spring d^{14} which is placed between the upper lug d^{12} and an adjustable screw-nut d^{15} on the slide

rod. The lower arm of the elbow-lever d^{10} is pivotally connected between the fulcrum of the elbow-lever d^{10} and its pivot connection with the slide-rod d^{11} with a clutch-rod d^{16} which engages by its opposite end a forked shifting lever d^{17} that actuates a clutch d^{18} on the driving-shaft s^1 so that immediately on the release of the short cam d^7 on the rock-shaft d^5 , due to the abutting of the cardboard fed by the cardboard machine against the stop-gage d , the lever d^8 is released and the clutch-rod d^{16} actuated so as to shift the clutch d^{18} on the driving-shaft S and move it out of gear with the gear-wheel g^3 and into gear with the sprocket-wheel and produce the instant arresting of the motion of the feed and guide-rollers a , a^1 and b , b^1 the stopping of the forward feed of the cardboard and the actuation of the cutting-knife. Simultaneously with the release of the lever d^8 the upper arm of the elbow-lever d^{10} is lowered and thereby a short lever e which is fulcrumed to the supporting frame f moved downwardly so that a pivot-rod e^1 , connected with the lower end of the lever e and guided in keepers e^2 of the upright f^1 , is raised and thereby a stop e^3 at its lower end released from a recess of a roller e^4 on the shaft s , whereby the actuating-shaft s can be rotated by the sprocket-chain and wheel transmission g , g^1 , g^2 from the driving shaft for reciprocating the cutting-knife k and cutting off the blank fed by the feed- and guide-rollers a , a^1 and b , b^1 against the stop-gage d .

The corrugated card-board which is fed to the proper length beyond the cutting-knife k is supported on two guide-plates h which are located at the lower ends of angular laterally-oscillating hanging-rod h^1 that are clamped at their upper ends to longitudinal rods h^x which turn loosely in bearings of transverse bars h^4 . The bars h^4 are supported by stationary rods h^5 from the ceiling, as shown in Figs. 3 and 4. To the transverse bar h^4 adjacent to the upright standards f^1 are clamped by set-screws h^3 sleeves h^2 through eyes of which are passed the inner ends of the rods h^x , which latter are provided with crank-arms h^6 that are pivotally connected with an oscillating rod h^7 which is fulcrumed to a central keeper h^8 on the transverse bar h^4 said rod h^7 being connected at its laterally-extended end with a vertical actuating rod h^9 which is guided in keepers h^{10} on one of the uprights f^1 and provided in its upper portion with a turn-buckle h^{11} for adjusting its length, and thereby the lateral motion or stroke of the hanger-rods h^1 . The lower end of the actuating-rod h^9 is provided with an antifriction-roller r which moves over the circumference of a cam r^1 at the right-hand end of the shaft s as shown clearly in Figs. 3 and 4. The actuating-rod h^9 is called into

action simultaneously with the cutting-off of the piece of cardboard by the vertically-reciprocating knife k , so as to oscillate the guide-plates h from their normally-horizontal position, shown in Fig. 3, sidewise into an inclined position, as shown in Fig. 4, and permit thereby the dropping of the cut-out blank of cardboard onto the pile of cardboards below the guide-plates. As soon as the blank of corrugated cardboard which is cut off is delivered to the pile, the guide-plates h are returned into their horizontal position so as to receive the next length of cardboard fed forward from the cardboard machine. The dropping of the blank releases also the stop-gage d and permits it to return into vertical position while the cutting knife is returned into raised position by the remeshing of the clutch with the driving-shaft S and the return of the intermediate parts of the clutch-unmeshing mechanism into their normal position, shown in Fig. 1, and reengagement of the lever d^8 with the cam d^7 , ready for the next cutting-off action of the knife. The return-motion of the intermediate clutch-releasing lever-mechanism is assisted by the tension of the helical spring d^{14} on the slide-rod d^{11} , simultaneously with the return-motion imparted to the guide-frame of the cutting knife by the roller e^4 cams k^6 and connecting-rods h^4 .

With each full rotation of the driving shaft the cardboard is fed forward beyond the cutting knife for the required length until it strikes the stop-gage, which instantly releases the intermediate lever-mechanism between the releasing cam of the stop-gage and the driving gear of the feed-rollers, so as to arrest the motion of the same while the stop-device of the knife actuating-mechanism is released and the latter reciprocated for cutting off the blank. Simultaneously the guide-plates for the blank are oscillated and the blank dropped clear of the same, the parts are then returned to their former or normal position and actuated by the next rotation of the driving shaft and so on until the required number of blanks of a certain width and length is obtained.

The intermittent stopping of the feed-motion of the cardboard, together with the actuation of the cutting-knife, when the cardboard arrives against the stop-gage d , by which the actuation of the intermediate lever mechanism, the ungearing of the feed-rollers and the downward motion of the cutting knife are produced, permits the automatic cutting-off of the blanks of card-board of any desired length as the same is fed from the cardboard machine, so that the blanks of the required size are obtained as the corrugated cardboard is delivered from the machine, and thereby a considerable saving in the manufacture of boxes, wrap-

pers and other articles from corrugated cardboard is obtained.

I claim:

1. A cutting-off attachment for machines for making corrugated cardboard, comprising intermittently-actuated feed-rollers, spaced guide-plates for the cardboard, bearings laterally and independently adjustable, for supporting said guide-plates, means for oscillating said guide-plates, a stop-gage suspended in the path of the cardboard, means between the stop-gage and the driving mechanism of the feed-rollers for interrupting the motion of the same, and a vertically-reciprocating cutting-knife adapted to cut off the proper length of cardboard as soon as it forms contact with the stop-gage.
2. A cutting-off attachment for machines for making corrugated cardboard, comprising intermittently - actuated feed - rollers, spaced guide-plates for the cardboard, bearings laterally and independently adjustable for suspending the guide-plates, means for oscillating said guide-plates in lateral direction, a stop-gage suspended in the path of the cardboard, means between the stop-gage and the driving mechanism of the feed-rollers for interrupting the motion of the same, a vertically guided cutting-knife adapted to cut off the proper size of cardboard as soon as the same forms contact with the stop-gage, means for intermittently reciprocating the cutting-knife, a stop device for the cutting knife and means for returning the stopping means of the feed-rollers and of the cutting knife into their normal position for the next actuation of the same.
3. A cutting-off attachment for machines for making corrugated cardboard, comprising intermittently - actuated feed - rollers, spaced guide-plates for the cardboard, bearings laterally and independently adjustable

for suspending the guide-plates, means for oscillating said guide-plates in lateral direction, an adjustable stop-gage, means for supporting the stop-gage in the path of the cardboard, means between the stop-gage and the driving mechanism of the feed-rollers for interrupting the feed-motion of the same, a vertically guided cutting-knife adapted to cut off the proper length of cardboard as soon as it forms contact with the stop-gage, means for vertically reciprocating the cutting-knife, a stop-device for the same and means for releasing the stop device and permitting the actuation of the cutting-knife.

4. In a cutting-off attachment for cardboard machines, the combination of intermittently - actuated feed - rollers, spaced guide-plates for the cardboard, bearings laterally and independently adjustable for suspending the guide-plates, an oscillating lever for operating said guide-plates, a connecting-rod connected with said lever, means for adjusting the length of said connecting-rod, a stop-gage for the cardboard, means for suspending the stop-gage in the path of the cardboard, a vertically guided cutting knife, means for intermittently reciprocating the cutting knife, a stop-device for said cutting knife, means for releasing said stop-device, a clutch device between the feed-roller driving means and cutting-knife actuating means, and a lever mechanism between the stop-gage and clutch-device for arresting the motion of the feed-rollers and cardboard simultaneously with the release of the stop-device of the cutting knife and actuation of the same.

In testimony, that I claim the foregoing as my invention, I have signed my name in presence of two subscribing witnesses.

SAMUEL A. GOLDBERG.
